UNITED STATES PATENT OFFICE.

CHARLES E. BLECHSCHMIDT, OF BELLEVUE, KENTUCKY, ASSIGNOR TO THE VICTOR SAFE AND LOCK COMPANY, OF CINCINNATI, OHIO.

DAY-LOCK FOR TIME-LOCK-OPERATED SCREW SAFE-DOORS.

SPECIFICATION forming part of Letters Patent No. 710,417, dated October 7, 1902.

Application filed January 9, 1901. Serial No. 42,637. (No model.)

To all whom it may concern:

Be it known that I, CHARLES E. BLECHSCHMIDT, a citizen of the United States, residing at Bellevue, Campbell county, State of Kentucky, have invented a certain new and useful Day-Lock for Time-Lock-Operated Screw Safe-Doors; and I do declare the following to be a full, clear, and exact description of the invention, such as will enable others skilled in the art to which it appertains to make and use the same, attention being called to the accompanying drawings, with the reference-numerals marked thereon, which form also a part of this specification.

This invention relates to improvements in safes where the doors are automatically unlocked by a time-lock or other means operating to render the safe accessible after a certain predetermined length of time has elapsed after the closing of the door.

It relates more particularly to safes having circular doors, screw-threaded around their edges and adapted to close the opening for which they are intended by engaging a similar thread provided around such opening. This screw engagement requires rotation of the door, for which reason this latter is supported accordingly. Bolts carried by it and adapted to enter into and occupy sockets when the door is fully screwed home prevent rotation necessary in reverse direction to unscrew the door. The withdrawal of such bolts proceeds automatically and is by the time-lock operating after a certain interval of time and during which the safe remains inaccessible. This interval of time comprises usually the hours between the close of business on one day and opening at the next, while during business-hours the safe usually remains open. There are often circumstances, however, which may render a temporary locking of the safe for shorter or longer time during these hours desirable. This would require the manipulation, winding, and setting of the time-lock in each case and also defer possibility of access to the particular time once set, all of which is objectionable at that time and for that particular purpose.

The object of my invention is therefore to provide means which permit the safe-door to be locked quickly and conveniently at any

time without requiring manipulation of the time-lock, permitting in the same manner the unlocking of the door at any time sooner or later thereafter and without having to depend on and wait for the exact moment as would otherwise be determined by the time-lock. This object is obtained by means permitting locking of the rotary part of the door to the non-rotary part thereof, thereby preventing the rotation of the door necessary to permit disengagement of its screw connection. These means must be and are independent of the time-lock-operated bolts and intervening mechanism.

In the following specification, and particularly pointed out in the claim at the end thereof, is found a full description of the invention, together with its operation, parts, and construction, which latter is also illustrated in the accompanying drawings, in which—

Figure 1 is a front elevation of a safe closed by means of a screw-door and provided with my invention. Fig. 2 is a side elevation thereof with parts broken away and the door shown partly in edge view and partly in section. Fig. 3 shows a front view of the safe-door with parts broken away and the door locked against rotation. Fig. 4 in parts of the preceding figure shows the locking means in a position which permits rotation of the door. Fig. 5 is a detail view and shows an end view of the locking means. Fig. 6 in a similar view shows a top view of these parts.

This invention is intended to be an improvement by addition to such safe constructions with screw-doors as are illustrated in my prior patents, particularly No. 622,753, issued on April 11, 1899, and in which construction a gear-train is used to rotate the door. The means for carrying out my invention are therefore constructed with particular reference to the construction shown in these patents.

10 is the front of a safe of customary construction provided with a circular opening to receive the circular door 11. This door on its front side is provided with an outwardly-projecting journal 12, fitted to occupy a bearing in a ring 13 and within which said door 100 is capable of rotation. Both are carried on a crane-frame 14, to which they are pivotally

held by vertically-disposed trunnions 15, which engage ring 13. Crane 14 is hinged at 16 to front 10 of the safe and provided with a handle 17, whereby the door may be swung to or from its opening.

The circular side or edge of the door is in part tapering or conical and in part straight or cylindrical, the largest diameter of the door being at its outside, from where to about half its thickness inwardly its diameter decreases on a taper, after which it continues again straight inwardly and at such reduced diameter for the balance of the thickness of the door. This tapering part of the periphery is stepped off, as shown at 18, while the straight part is provided with a screw-thread 19, fitted to a similar thread within the door-opening. The parts are so arranged that rotation of the door when nearly closed causes the screw-threads to engage, and when such engagement has reached its limit the stepped part 18 has also reached its proper position and is in close fit and contact with the similar stepped part of the door-opening, thus closing this latter tightly. At that time bolts 21, carried by the door, have also arrived opposite sockets within the door-opening of the safe-front, and at the moment rotation of the door ceases these bolts advance into and occupy such sockets. This prevents rotation of the door in reverse direction, and thereby locks the same against opening and access. The rotation of the door is by means of a gear-train consisting of a cog-wheel 22 and a pinion 23, which latter is seated on ring 13 and carries an outwardly-projecting key 24, fitted to the socket of a suitable crank-handle 25, used for manipulation while rotating the door. Cog-wheel 22 is rigidly attached to the door by being connected to the face of journal 12, projecting therefrom, thereby transmitting the rotation received from pinion 23 to it, and by projecting over the non-rotary ring 13 it serves as a collar to hold journal 12 of the door in place in its bearing within said ring. The attachment of said cog-wheel is by means of a screw connection, and for centering it has a bore which receives a circular flange or boss 26, projecting outwardly from journal 12.

The means operating automatically and whereby the bolts are caused to so advance at the time when the door has been screwed home and rotation ceases are not new and therefore not shown, nor are the means which operate to retract these bolts to permit rotation in reverse direction for unlocking and opening of the door. These latter means consist of a time-lock which must be manipulated, wound, and set every time the safe is to be locked, after which the action of this time-lock must be awaited before access to the safe can be had. This renders the use of the time-lock inconvenient when the safe is to be locked only temporarily and for indeterminate limited lengths of time during the day, and for such purpose and to enable such locking I

have provided locking means whereby the safe-door may be locked in its closed position and unlocked at any time thereafter independently of the time-lock. The means for doing such are also entirely independent from the means and intermediate mechanism operating in conjunction with the time-lock. The locking in this latter case is, as before mentioned, by bolts 21, which prevent rotation of the door in reverse direction, necessary to unscrew it by locking it to the adjacent parts of the safe-front. The means I provide also prevent such rotation, but do it by locking the rotary door to the non-rotary part thereof and by preventing rotation of the gear-train necessary to unscrew the door. For such purpose I lock the door to ring 13, which forms a part of it, being its support, but does not rotate therewith. The locking-bolt 27 I use for such purpose may be operated by any suitable locking devices; but by preference I use a so-called "combination-lock," being a permutable tumbler. Everything pertaining to these locking means is carried by and attached to the door, occupying a space or housing 28, obtained by recessing the front of boss 26, while the end of bolt 27 extends into a guideway 29, cut partly into boss 26 and partly in the inner edge of gear-wheel 22, through the entire thickness of which it extends. This bolt 27 is so located as to be capable of meeting these two parts of its guideway, and it is of such depth as to project rearwardly beyond gear-wheel 22 and into a recess 31, cut into the face—that is, front side of ring 13 back of said gear-wheel—when this recess is alined with the guideway. (See Fig. 5.) The bolt is thus capable of simultaneously occupying these three recesses—that is, the two parts of its guideway in boss 26 and gear-wheel 22 and recess 31 in ring 13—and which constitutes its locking position, recess 31 being its keeper, and since this latter is contained in ring 13, which is incapable of rotation, it is clear that the door is effectually locked against the rotation required to unscrew it. For unlocking, bolt 27 is retracted sufficiently to leave this recess, which forms its keeper within ring 13. For so moving the bolt any suitable lock mechanism may be used; but, as above stated, I prefer to use the customary permutation-lock consisting of a number of tumblers 32, the notches of which when alined by means of a handle 33 permit latch 34 to be engaged by said tumblers, after which the bolt may be moved. The alinement of the tumblers is after certain rules based on a combination of numbers known to the user and selected from the figures indicated by a dial 35 on the outside of the door. This dial is secured to a cover 36, provided to inclose the gear-train and to improve the appearance of the safe. The parts of this lock are so arranged and located as to have keeper 31, bolt 27, and its guideway in alinement with each other when the door is fully screwed home and ready for locking or unlocking. By

preference this position is also a horizontal one. To prevent the bolt from dropping out of its locking position during rotation of the door, I provide a stop 37, located in the path 5 of a heel 38 on latch 34. The locking of the screw-door by these means proceeds quickly and conveniently, also its unlocking, and this latter may be performed at any time after the locking and whenever required without having to await the operation of the time-lock. When so locking the door, the mechanical means operating to automatically move bolts 21 into their locking position are of course inoperative. There is no connection of any 15 kind, mechanical or otherwise, between the means comprising the two locking systems, and when closed and locked at night by the time-lock mechanism the knowledge of the combination to move bolt 27 or any tampering 20 with this latter would be of no avail to aid in gaining access to the safe. Instead of being carried by the rotary part of the door this day-lock might be applied to the stationary one, which, however, would be merely a reversion 25 of location.

Having described my invention, I claim as new—

In means for locking the rotary screw-door of a safe, the combination of a boss 12, forming the journal on which such a door is supported for rotation, a non-rotary ring 13 forming a bearing within which this journal is supported, a crane-frame 14 on which this ring is carried, a handle 17 rigidly connected 30 to this frame whereby the door is moved toward or from the door-opening, a gear-wheel 35

22 rigidly connected in front of ring 13 to the face of boss 12 which projects from the door for rotating the same within ring 13, a boss 26 on which this gear-wheel is centered, a 40 pinion 23 on ring 13 in mesh with the gear-wheel, a key 24 thereon intended to receive a detachable handle to rotate the pinion and gear-wheel for purposes of rotating the door, recesses forming a combined boltway, one 29, 45 partly in boss 26 of the door and partly in the inner edge of gear-wheel 22, the other 31 in the face, that is front side of ring 13 back of the gear-wheel, said recesses so located with reference to each other that the one in gear-wheel 22 arrives in alignment over the recess in ring 13 at the time when the door is fully screwed home, a recess 28 in boss 12 of the door, a bolt therein adapted to occupy recess 29 and of such depth as to project also rearwardly through and beyond the thickness of gear-wheel 22 and into recess 31 in ring 13 so as to simultaneously occupy the same when aligned with recess 29 in front of it, and lock mechanism fixedly secured within recess 28 50 of the door and whereby the bolt may be so moved into the aligned recesses after which it prevents the rotation of the gear-wheel necessary to unscrew the door by locking the same to the ring 13 and to boss 26 on the door. 55

In testimony whereof I hereunto set my hand in the presence of two witnesses.

CHARLES E. BLECHSCHMIDT.
